UNITED STATES PATENT OFFICE

2,620,721

REVERSIBLE WINDOW FAN OR VENTILATOR

Carl Krauss, Chicago, Ill.

Application February 12, 1949, Serial No. 76,160

3 Claims. (Cl. 98—94)

1

The present invention relates to a novel window fan or ventilator construction and assembly that is adjustable for mounting in a window, transom or other opening, and more particularly to such a ventilator having a fan that is reversible and equally effective in drawing fresh air into a room or other enclosure, or in exhausting air from such room or enclosure.

It is, therefore, an object of the present invention to provide a novel fan or ventilator unit that is reversible and equally effective in drawing fresh air from the outside into an enclosure as well as exhausting stale air from the enclosure. This is accomplished by means of my novel ventilator construction and assembly adapted to be mounted in a window, transom or other opening and in which assembly is provided a novel dual passage arrangement that directs and assures maximum passage of air therethrough, and whereby the air may be forced through the ventilator in either direction and thereby either draw fresh air from the outside atmosphere into the enclosure or to exhaust the stale air, smoke fumes or cooking odors from the enclosure to the exterior or outside atmosphere.

Due to this novel arrangement for tunnelling the air therethrough and the manner of positioning and reversibly mounting the fan therein, the same amount of fresh outside air will be brought into the room or enclosure in one operative position of the fan as will be exhausted when the fan is operating for exhausting the stale or warm air from the room. Recirculation of the air is reduced to a minimum so that if the fan is adjusted to the position for the intake of air, the operator is assured that he is not recirculating air taken from the interior of the room or enclosure but is tunnelling in the desired fresh air from the outside atmosphere.

The present invention further comprehends a novel portable window ventilator unit having a reversible fan and provided with a novel manual control by which the operator may quickly and easily reverse its operation, and with a novel detent or latch arrangement for retaining or holding the fan and motor assembly in the desired operating position.

Another important object of the present invention is the provision of a novel pivotal mounting for the reversible exhaust or intake fan and its motor in the main panel or frame.

A further important object is the provision of a novel protective grill or perforated guard detachably mounted upon the main panel or frame in such manner that it may be easily and quickly

removed for access to the fan assembly, its pivotal mounting and the electrical wiring, all carried by the main panel or frame. This is an important feature as it permits ready access to the motor and mechanism for maintenance, assembly and disassembly of the unit by simply removing the protective guard or grill which carries none of the operating parts.

Further objects are to provide a construction of maximum simplicity, efficiency, economy and ease of assembly and operation, and such further objects, advantages and capabilities as will later more fully appear and are inherently possessed thereby.

15 The invention further resides in the construction, combination and arrangement of parts illustrated in the accompanying drawings, and while there is shown therein a preferred embodiment, it is to be understood that the same is susceptible of modification and change, and comprehends other details, arrangements of parts, features and constructions without departing from the spirit of the invention.

20 In the drawings:

25 Figure 1 is a view in end elevation of the novel reversible window fan or ventilator projecting into a room or other enclosure and showing the manner of mounting it in a window opening, the window sash and window sill and ledge being shown in vertical cross-section.

30 Figure 2 is a view in front elevation of the novel reversible window fan or ventilator mounted in the window opening and taken from the interior of the room, the window sash and frame being broken away for a more complete understanding of the manner of mounting the ventilator in the opposite side jambs and resting upon the window sill.

35 Figure 3 is an enlarged view in front elevation of the novel ventilator assembly with the protective screen or perforated guard removed.

40 Figure 4 is a view in vertical cross-section through the reversible window fan or ventilator, the motor mounting and fan being adjusted to the position for drawing air into the room or enclosure.

45 Figure 5 is a view, part in end elevation and part in vertical cross-section taken in approximately the same plane as Fig. 4, but showing the motor mounting and fan reversed or rotated through 180° for exhausting the air from the room or other enclosure.

50 Figure 6 is a view in front elevation of the main panel or frame with its Venturi passage or throat, and their end panels, and showing the manner of adjusting the width of the ventilator

to fit windows or other openings of different widths by sliding adjustment of the telescoping end panels at the opposite ends of the main frame.

Fig. 7 is a view in perspective of one of the telescoping end panels.

Fig. 8 is a fragmentary enlarged view in vertical cross-section through the main and a telescoping end panel and showing the manner of locking these panels in adjusted position, the end flange of the end panel being omitted for more complete disclosure.

Fig. 9 is a fragmentary enlarged view, part in vertical cross-section and part in side elevation, showing the resilient mounting for journaling or pivotally supporting the upper end of the pivot rod or shaft which carries the fan and motor assembly.

Fig. 10 is a fragmentary enlarged view in vertical cross section through the pivot box, the pivotally mounted handle and its locking detent mechanism for retaining the handle, fan and motor assembly shown in Fig. 3 in exhaust or intake position.

Fig. 11 is an enlarged top plan view of one of the spaced embossments or protuberances on the pivot box for receiving the locking detent and provided with a stop to limit rotation of the handle in one direction.

Referring more particularly to the illustrative embodiment disclosed in the drawings, the novel reversible window fan or ventilator 1 is shown as comprising a main frame or panel 2 provided with slidably adjustable end sections or end panels 3 and 4 adapted to be mounted in an opening such as a window opening in a window frame 5. These panels 2, 3 and 4 are preferably formed of metal or other material suitable for the purpose. The main frame 2 of the ventilator is provided with a top flange 6 and a bottom flange 7 adapted to slidably receive the oppositely disposed end sections or panels 3 and 4, each provided with an arcuate edge or cut-out 8, an in-turned top flange 9, an in-turned bottom flange 11 and an in-turned end flange 12 provided with open key slots 13 adapted to receive a screw, headed pin or the like 14. These screws or pins are mounted in the moldings 10 in the opposite side jambs 15 of the window frame in such manner as to project inwardly into the window opening, and whereby the ventilator is retained or held in operative position when supported upon the window sill and ledge or mullion 16 and the end sections or end panels 3 and 4 are rigidly connected to the main frame 1. Suitable locking means such as screws or bolts 17 connecting the overlapping top flange 6 of the main frame 2 and the top flange 9 of the end panels 3 and 4, lock these adjustable end panels onto the main frame to form a rigid assembly of a predetermined or required width. This is accomplished by providing each upper flange 9 of an end panel with an elongated slot 20 through which passes the bolt 17 and which bolt is locked in position by a stationary nut 17a drawing the lower flange 11 of the end panel against the inturned lip or edge of the flange 7 (see Fig. 8).

The arcuate edges 8 are so contoured that when the end sections or end panels 3 and 4 are forced inwardly to their innermost position (Fig. 6), these edges encompass a tubular or cylindrical member 18 of substantial length or depth centrally disposed within the main frame 2 and forming a double throat or passage for confining and directing the air therethrough. To draw

or tunnel the air through this passage, there is provided therein a fan or air circulating means 19 mounted upon the rotating shaft 21 of a motor 22, all supported or carried by split clamping sections 23 and 24 forming an encompassing band or collar about the motor 22 and with the lower clamping section 24 secured to an end of a pivot rod 25 and the upper clamping section 23 secured to an end of a pivot rod 26.

The pivot rod 25 is offset at 27 and with its offset end 28 passing through the cylindrical member 18 and journalled or rotatably mounted in a pivot box or bracket 29 secured in any suitable manner to the exterior of the member 18. The pivot rod 26 is offset at 31 and its offset end 32 also projects through the cylindrical member 18 and is journalled or rotatably mounted in a pivot box or bracket 33. In each pivot box is provided a rubber grommet 30 in which the offset ends 28 and 32 are rotatably or pivotally mounted, and which mounting absorbs and prevents vibrations of the motor and fan assembly from being transferred to the metal parts of the main panel and enclosure through direct metal to metal contact. Upon this end 32 where it projects through the pivot box or bracket 33 is pinned or keyed a handle 34 and upon the upper surface of the pivot box 33 at the opposite sides of the projecting end 32 and in the path of the pivotal movement of this handle are provided embossments or protuberances 35. These embossments are spaced apart 180° and each provided with a depression 36 adapted to receive a detent or projection 37 on the underside of the handle and thereby lock or hold the handle against accidental or unintentional release, but permitting the operator to manually release the handle and turn it and the fan and motor assembly about the offset pivot rods 25 and 26 through 180°, whenever it is desired to reverse the motor from intake to exhaust, or vice versa. To prevent the handle from rotating through an arc of more than approximately 180° and beyond the embossments 35, a stop 38 is provided immediately adjacent and to the rear of each embossment.

When the reversible window fan or ventilator is located in the window, transom or other opening and the fan is positioned in the cylindrical member or tunnel 18 as in Fig. 4, air is drawn into the room or enclosure from the exterior or outside atmosphere. To prevent danger to the occupants of the room, the fan is protected and covered by a protective grill or perforated guard 41 detachably or removably mounted upon the exterior of the main frame 2 by bolts 42 and knurled or removable nuts 43 that permit its ready attachment or detachment.

By merely disengaging the handle and locking detent from the position shown in Fig. 4 and rotating the handle and the fan and motor assembly carried by the rods 25 and 26 through an arc of 180°, the motor and fan are located in the position of Fig. 5 and in which position the fan 19 draws air from the interior of the room or enclosure through the protective grill or perforated guard and discharges it outwardly through the double air tunnel 18 to the outside atmosphere.

By operating the fan in the confined space of the tubular or cylindrical member or air tunnel 18, a dual passage is provided (1) for the air that is drawn into the room when the fan is operating as an intake fan, and (2) for the air exhausted from the room when it is operated as an exhaust fan. This effectively controls and confines the

passage of air in either direction of flow and assures maximum flow of fresh air into the interior of the room or enclosure, or when reversed, assures maximum exhaust of the stale air, cooking odors or smoke fumes.

In the installation, the novel reversible window fan or ventilator assembly, which is portable and may be installed wherever needed, may be quickly adjusted to the desired width of the window opening, transom or other opening in which the ventilator is to be mounted. This is accomplished by loosening the screws or bolts 17 and stationary nuts 17^a and withdrawing the end sections or end panels 3 and 4 by reason of the elongated slots 20 to the proper width. Suitably spaced screws or headed pins 14 are secured in the opposite moldings 10 of side jambs 15 of the window frame 5 to receive the end flanges 12 of the adjustable panels 3 and 4. These screws are to be so placed that the lower end of the ventilator seats or rests upon the mullion or ledge 16 and in which position the screws or pins 14 are disposed in the upper ends of the key hole slots 13 (see Fig. 1). The screws 17 in the top flange 6 of the frame or main panel 1 are tightened when the end or extension panels 3 and 4 are extended to the proper width, causing the stationary nuts 17^a to exert upward pressure against the upper flanges 9 of the end panels 3 and 4 and the lower flanges 11 of these end panels are drawn up against the inturned edge 7^a of the bottom flange 7 of the main panel. The pressure thus exerted provides an effective means of locking each adjustable end panel to the main panel by the manipulation of but a single screw or bolt. This novel arrangement facilitates adjustment of the panels and eliminates binding and individual fitting of panels encountered in other makes and designs of telescoping panels. In this position the protective grill or perforated guard 41 projects into the room or enclosure to be ventilated and protects the occupants, and especially children, from contact with the fan blades. The lower sash rail 44 when lowered to the position shown in Figs. 1 and 2, limits the flow of air in the desired direction through the dual passage.

An electric cord 45 is connected at one end to the motor 22 and at the other end is provided with a plug (not shown) that may be connected to any socket or wall outlet for supplying current to the motor. This cord 45 is preferably provided with a switch at or adjacent the ventilator or reversible fan unit to permit the operator to energize or de-energize the motor without the necessity of inserting or removing the plug. The cord adjacent to where it is connected to the ventilator, is led through an insulating grommet 46 in a bracket 47 mounted on the main frame 2, through the bracket or pivot box 29 providing the pivotal mounting for the offset end 28 of the pivot rod 25, and through the tubular or cylindrical member 18. To prevent the end of the cord entering the motor from becoming twisted or damaged as the motor and fan are repeatedly rotated from the intake to the exhaust positions, an arm 48 is preferably mounted on the pivot rod 25 and deflects the cord to one side or the other as the motor and fan assembly are rotated back and forth from one position to the other.

By removing the protective grill or guard 41 by removal of the four nuts 43 from the screws or bolts 42, complete access may be had to the fan, motor and associated parts so that the assembly, disassembly or replacement of any of the parts may be readily accomplished. This pro-

tective grill or guard readily and easily slips over the cylindrical or dual member 18 and has its lower and upper surfaces or panels 49 recessed to encompass the pivot box or brackets 29 and 33, respectively, in which the offset ends

10 of the rods 25 and 26 are pivotally mounted. Except for the embossments 35 and stops 38 provided on the upper pivot box or bracket 33 and which are omitted from the lower one 29, these boxes or brackets are preferably the same. The lower box 29 in addition to providing a pivotal mounting for the offset end of the rod 25, provides a splicing box to connect the wires from the motor to the feed cord.

15 From the above description and the disclosure in the drawings, it will be readily appreciated that the present invention comprehends a novel reversible window fan or ventilator that is highly efficient and effective in operation, and one that 20 is readily adjustable and of light weight so that it may be quickly removed or installed wherever desired or required.

Having thus disclosed the invention, I claim:

1. A reversible window fan adapted to be 25 movably mounted in a window frame or other opening in an enclosure, comprising an adjustable panel assembly the width of which may be adjusted to accommodate openings of varying widths, means for supporting the panel assembly 30 in the frame, a cylindrical member rigidly mounted in the assembly and having its opposite ends outwardly flared for directing the entering air, a fan and motor unit rotatably mounted in the cylindrical member about a vertical axis and 35 through an arc of 180° whereby in one position fresh air from the exterior is drawn through said tubular member and into the enclosure, and in another position stale air, cooking odors or smoke fumes are drawn from the enclosure 40 through said tubular member and exhausted to the exterior, and a perforated grill detachably mounted on the side of the panel assembly facing the enclosure to enclose said cylindrical member and fan and protect the occupants of the room 45 against contact with the fan, but when the grill is removed access is had to the fan, motor and associated mechanism, all carried by the panel assembly.

2. A reversible window fan adapted to be 50 removably mounted in the frame defining a window opening, comprising a ventilator frame including a central and adjustable telescoping end sections adapted to be adjusted to the width of the opening and detachably mounted in the window 55 frame, a tubular member mounted in the central section and defining an air passage of substantial length through the ventilator frame through which the incoming or outgoing air is directed, the opposite ends of said tubular member being flared outwardly to direct and tunnel the air entering either end thereof, a fan and motor disposed within the passage of the tubular member, oppositely extending rods having one end 60 supporting the motor and fan substantially centrally of said passage and having their other end offset and journaled in the tubular member to permit the fan and motor to be rotated through 180° for directing air through either end of the tubular member and with the fan located within the tubular member in either position, and a removable protective grill enclosing the tubular member, fan and motor.

3. A reversible window fan adapted to be 70 mounted in an opening such as window, transom and the like for either drawing fresh air into

a room or for exhausting stale air, smoke fumes, cooking odors and the like from the room, comprising an adjustable frame adapted to be adjusted in width and whereby it may be mounted in openings varying in width and including a central panel and end panels each flanged at the top and bottom for longitudinal sliding adjustment of the end panels, means for connecting the flanges of the central and end panels in adjusted position, an inturned end flange on said end panels for detachably supporting the adjusted frame in the opening, a tubular imperforate member mounted in said central panel in inwardly spaced relation from its top and bottom flanges, said member providing an elongated passage with its outer ends outwardly flared for directing and controlling the passage of air therethrough in either direction, a reversible fan and motor mounted for rotation about a vertical axis in said tubular member, a handle projecting above the frame for rotating the fan and motor through an arc of 180° for operating the fan in one position in which it draws the outside air

into the room and in another position in which it exhausts the air from the room to the outside, and means for locking the handle, motor and fan in either operative position.
